Patented Apr. 17, 1928.

UNITED STATES PATENT OFFICE.

ANDY HINKLE, OF ATLANTA, GEORGIA.

PICKER-STICK CHECK.

Application filed August 30, 1928. Serial No. 132,608.

This invention relates to improvements in picker stick checks for looms, and the primary object is to provide a check of simple, inexpensive and durable construction, having a movable or swinging part designed to start on a light tap from the picker stick and to stop suddenly at the end of its travel without any possibility of rebounding.

A further object is to furnish a picker stick check having a movable part adapted to travel at any rate of speed necessary to accommodate the picker stick, and capable of operating without the use of any grease or oil.

With the foregoing objects outlined and with other objects in view which will appear as the description proceeds, the invention consists in the novel features hereinafter described in detail, illustrated in the accompanying drawings, and more particularly pointed out in the appended claims.

Referring to the drawings:

Figure 1 is a face view of part of one end of a loom, showing the improvement attached thereto;

Fig. 2 is a front view of my novel check; and

Fig. 3 is an end view of the check looking in the direction of the line 3-3 in Fig. 2.

In the drawings 1 indicates the lay of a loom of any well known type, in which a shuttle 2 is thrown through the shed by a picker 3 secured to the top of the picker stick 4. In the operation of the loom, the picker stick travels from its full line position to its dotted line position, Fig. 1, in throwing the shuttle and returns again to its full line position when the shuttle is thrown back again by the picker stick on the opposite side of the loom. It is essential that the picker stick remain in one of those two positions instead of occupying some intermediate position, which frequently happens when no picker stick check is used and the picker stick strikes positive unyielding stops at the ends of its stroke.

I eliminate this tendency on the part of the picker stick to rebound by providing a novel checking device against which the picker stick strikes when near the end of its stroke in either direction, and which absorbs the excess energy of the stick and brings it gently to rest in its correct position.

This novel checking device includes a hanger bar 5 having its upper end rounded and connected to an angular bracket 6, the

hanger bar and bracket having a hole 7 to receive a bolt 8 in attaching the bar to the loom 1. The bracket 6 fits tightly against the under side of the wooden bar 9 of the loom and prevents the hanger strap from rocking. Due to this construction the bar 5 is held rigidly in place.

The hanger bar supports a horizontal bar 10 which is relatively short and rigidly secured to the bar 5 by suitable fastening means such as bolts 11. A triangular shaped stop block 12 rests on the bar 10 and is rigidly secured to the bar 5 by means of a bolt or the like 13.

The end portions of the horizontal bar are pivotally connected by pairs of rocker arms 14 to an upper connecting rod or bar 15, the connections being pivotal and provided by bolts or the like 16.

The upper bolts 16 extend rearwardly from the rod 15 and carry a pair of retaining rods 17, the pair of retaining rods being spaced apart on the bolts by stops 18 which may be washers of leather or the like, to cushion the picker stick which moves in a retaining frame consisting of the rectangular space bounded on its sides by the retaining rods 17 and on the ends by the stops 18. The forward one of the retaining rods 17 is spaced from the bar 15 by washers 19 arranged on the upper bolts 16, and a pin 20 on the bar 15 projects rearwardly into the space between the bar 15 and the front retaining rod 17. This pin is located at the central portion of the bar 15 and it is connected to the upper end of a coil spring 21, the latter having its lower end fixed to a pin 22 which projects rearwardly from the bar 10. A guard strap 23 extends about and protects the lower end of the spring and the pin 22, and has its ends secured to the lower bolts 16.

In the operation of the device, we will assume at the start, that the parts are in the position shown in Fig. 1, that is with the left-hand pair of rocker arms 14 vertically disposed and the right-hand pair of rocker arms extending substantially horizontal, and with the picker stick near the end A of the retaining frame. In this position the upper bar 15 lies on the inclined surface 24 of the stop block 12 and is held in this position by the spring 21, due to the fact that the upper end of the spring is moved over to one side of the center of the strap 5. Now when the picker stick 4 moves toward the left, it will

strike the stops 18 on the upper left-hand bolt 16 and it will then pull along the parts 14, 15 and 17 against the tension of the spring 21, until the latter passes to the opposite side of a central vertical line, that is, passes over dead center. After this, the spring will tend to rapidly move the parts toward the left until the rocker arms have moved the parts 15 and 17 to the dotted line position shown in Fig. 1, at which time the bar 15 will come to rest gently against the surface 25 and the picker stick will be halted and prevented from rebounding.

This movement has thrown the shuttle 2 over the lay toward the left end of the latter, and subsequently the picker stick on the opposite end of the lay throws the shuttle back. The shuttle in returning to its original position will strike the picker stick and the picker stick will move freely until it strikes the stops at the right end of the bars 15 and 17, and then the parts will move toward the right retarded by the spring 21, until the latter passes dead center, after which it will function to speedily move the parts into the full line position in Fig. 1. Any rebound of the check or picker stick will then be prevented by the overbalanced bar 15, and the particular rocker arm 14, which at this time is in a substantially horizontal position.

In actual practice the strap 5, which is about 3 inches wide and $1\frac{1}{8}$ inch thick, is rigidly secured to the loom by the bolt 8, and the parts 10 and 12 are rigidly attached to this strap, while the other parts are mounted for relatively free movement. Furthermore, the front retaining rod 17 and the strap 23 act as guards for the spring 21 and prevent the picker stick from contacting with said spring.

From the foregoing it is believed that the construction, operation and advantages of the invention may be readily understood, and I am aware that changes may be made in the details disclosed without departing from the spirit of the invention as expressed in the claims.

What I claim and desire to secure by Letters Patent is:

1. A picker stick check for looms including a retaining frame provided with stops between which a picker stick is adapted to oscillate, a plurality of swinging arms carrying said frame, and spring means connected to the frame and adapted to retard the movement of the frame for a portion of its travel and to assist in its movement during the remainder of its travel.

2. A picker stick check for looms including a checking member provided with stops faced with leather or like resilient material between which a picker stick is adapted to reciprocate, supporting means for the checking member and spring means adapted to

retard the movement of the checking member during a portion of its travel and to assist in the movement during another portion of its travel.

3. In a picker stick check for looms, a retaining frame adapted to be reciprocated by a picker stick, and means associated with said retaining frame for retarding the movement of the latter during a portion of its travel and to assist in its movement during another portion of its travel.

4. A picker stick check for looms comprising a supporting member, a bar carried by the supporting member, rocker arms carried by the bar, a retaining frame carried by the rocker arms, and spring means connected to the retaining frame and the bar for retarding the movement of said frame during a portion of its travel and to assist in its movement during another portion of its travel.

5. A picker stick check for looms including a supporting member, a bar carried by said member, a retaining frame pivotally spaced from said bar by a plurality of rocker arms, said retaining frame being adapted to be reciprocated by a picker stick, and spring means associated with the retaining frame and adapted to retard its movement during a portion of its travel and to assist in its movement during another portion of its travel.

6. A picker stick check for looms comprising a hanger strap provided at one end with an angular bracket adapted to be rigidly secured to a loom, a supporting bar arranged at the other end of said strap, a retaining frame, rocker arms pivotally connected between the supporting bar and the retaining frame, said retaining frame being adapted to be reciprocated by a picker stick, and means for retarding the movement of the last mentioned member during a portion of its travel and to assist in its movement during another portion of its travel.

7. A picker stick check for looms including a hanger strap, a supporting bar carried by the strap, rocker arms pivotally connected to said bar, a retaining frame carried by the rocker arms and adapted to be reciprocated by a picker stick, and spring means to retard the movement of the retaining frame during a portion of its travel and to assist in such movement during another portion of its travel in the same direction.

8. A picker stick check for looms comprising a hanger strap, a supporting bar carried by the strap, rocker arms pivotally connected to the supporting bar, a retaining frame carried by the rocker arms above said supporting bar and adapted to be reciprocated by a picker stick, and a coil spring connecting the central portions of the last mentioned member and said supporting bar.

9. A picker-stick check for looms comprising

ing a supporting structure, rocker arms having certain of their ends pivotally connected to the supporting structure, a retaining frame pivotally connected to the other ends 5 of the rocker arms, and a spring connecting said frame to the supporting structure and adapted to retard the movement of the frame during a portion of its travel in one direction and to assist in moving said frame 10 during another portion of its travel in the same direction.

10. A picker stick check for looms comprising a supporting structure, a stop block carried by the supporting structure and having 15 oppositely inclined faces, rocker arms pivotally connected to the supporting structure, a retaining frame pivotally connected

to the rocker arms and adapted to be moved by a picker stick during reciprocation of the latter, and a spring connecting the central 20 portions of the retaining frame and the supporting structure.

11. A picker stick check for looms as claimed in claim 10 including stops arranged in the ends of the retaining frame 25 and adapted to be struck by a picker stick.

12. A picker stick check as claimed in claim 10 including guards connected to the supporting structure and retaining frame to prevent the picker stick from contacting 30 with said spring.

In testimony whereof I affix my signature.

ANDY HINKLE.
